Application November 3, 1941, Serial No. 417,589

4 Claims. (Cl. 179—171)

This invention relates to an amplifier system and particularly relates to a new and improved stabilized amplifier system.

In conventional amplifiers, a plurality of amplifier tubes are connected in cascade relation, that is, the output circuit of one tube is always coupled to the input circuit of the following tube. In such amplifiers, a common voltage source is provided for supplying operating voltages to all of the amplifier tubes. This common voltage supply represents a connection between the input and output circuits of the various amplifier tubes and, therefore, such amplifiers tend to oscillate at a low frequency, which effect is generally termed "motor boating." This instability and the oscillations due thereto can be suppressed by providing by-pass condensers of extremely large capacity and de-coupling resistors of very high value. The use of very large condensers is undesirable because of cost and space requirements, while the use of very high de-coupling resistors is undesirable because of the losses incurred thereby.

It is the object of the present invention, therefore, to provide a new and improved amplifier system of increased stability, high efficiency, and low cost.

In accordance with the present invention, there is provided an amplifier system, comprising a plurality of amplifier tubes connected in cascade relation, each having an anode. A common source of operating voltage is provided for all anodes. A load impedance is connected to the anode of one of the tubes and a means including an impedance element for connecting the anode through the load impedance to the common voltage source. A second one of the tubes immediately following the first-named tube in the amplifier system is provided with an electrode adapted to collect a portion of the electron stream in the tube and, also, adapted to be maintained at a substantially steady potential. Finally, means, including a selective network and the above-mentioned impedance element, are provided for connecting the electrode of the second tube to the common voltage source.

For a better understanding of the invention, together with other and further objects thereof, reference is had to the following description, taken in connection with the accompanying drawing, and its scope will be pointed out in the appended claims.

The single figure of the accompanying drawing shows a schematic circuit diagram of an amplifier system embodying the present invention. This amplifier system comprises amplifier tubes 1, 2 and 3, connected in cascade relation between input terminals 4, 5 and output terminals 6, 7 for developing an amplified signal at the terminals 6, 7. While three amplifier tubes have

been shown, it is understood that the invention is not restricted to this number of tubes. The circuits in which tubes 1 and 2 are connected are of conventional design for amplifier tubes including screen grids and suppressor grids. However, they will be briefly described. The input terminals 4 and 5 are coupled to the control grid of the tube 1 for applying the input signal thereto by means of a coupling condenser 8 and a grid leak resistor 9. For developing the desired operating bias voltage for the tube, there is connected in its cathode circuit a resistor 10 shunted by a by-pass condenser 11. The suppressor grid of tube 1 is directly connected to the negative terminal of a common voltage source schematically indicated by a battery 12. The screen grid of tube 1 is held at a predetermined potential by connecting the same to the positive terminal of voltage source 12 through a resistor 13. For by-passing alternating screen grid currents, there is provided a condenser 14 connecting the screen grid with the negative terminal of the voltage source 12. Finally, the anode of tube 1 is connected by way of a load impedance including a resistor 15 and an inductance element 16, connected in series relation, and a de-coupling resistor 17 to the positive terminal of the voltage source 12, as shown. A condenser 18 is connected between the lower end of the inductance element 16 and the negative terminal of voltage source 12 for providing an alternating current path therebetween, thereby by-passing the de-coupling resistor and the common voltage source. The output circuit of tube 1 is coupled to the control grid of tube 2. Since the circuit of tube 2 is the same as that of tube 1, it is not deemed necessary to describe the same in detail and corresponding elements thereof are indicated in the drawing by the same numerals, accompanied by a distinguishing index.

The output circuit of tube 2 is coupled to the control grid of tube 3 and the circuit of tube 3 is the same as the circuits of tubes 1 and 2, with the exception of a distinguishing feature. Since the circuit of tube 3 is similar to those already described, it is not believed necessary to repeat the description, and corresponding circuit elements are indicated in the drawing by the same numerals accompanied by a distinguishing index. While the screen grids of tubes 1 and 2 are connected by way of resistors 13 and 13', respectively, to the positive terminal of the common voltage source 12, it will be noted that the circuit of tube 3 is not provided with such a connection. Instead, there is provided a resistor 19, connecting the screen grid of tube 3 with the junction point of inductance element 16' and resistor 17' in the output circuit of tube 2. The resistor 19 in combination with condensers 14'' and 18' forms a selective network

passing certain low frequencies only and attenuating all others.

In operation, an input signal is applied to the input terminals 4 and 5, which is amplified in the conventional manner by means of tubes 1, 2 and 3, to develop an amplified signal across the output terminals 6 and 7. In case of a shock excitation, such as may be due to the surge occurring when initially switching on the amplifier system or which may be due to any other type of surge, a voltage pulse could be produced in the output circuit of tube 3 which, by way of the common voltage source 12, would be applied in proper phase to the input circuits of certain other amplifier tubes and cause the amplifier to oscillate. A negative voltage pulse across the load impedance comprising resistor 15' and inductance element 16' of the tube 3 would be caused by a positive voltage pulse appearing in the output circuit of tube 2, which pulse is applied to the control grid of tube 3. Due to the presence of the novel feature according to this invention, however, a positive pulse in the output circuit of tube 2, is also applied to the screen grid of tube 3, since condenser 18' represents an appreciable impedance at lower frequencies, at which the oscillations occur. As the screen grid current characteristic of a tube is much like the anode current characteristic of a triode tube of low plate resistance, a relatively small change in screen grid voltage effects a relatively large change in screen grid current. Therefore, the positive pulse applied to the screen grid of tube 3 causes a current pulse to flow through the cathode screen grid space of tube 3, resistor 19, resistor 17' and voltage source 12, and a negative voltage pulse is developed across resistor 17' which tends to counteract the positive pulse applied to the control grid of tube 3 by making the junction point of resistor 17' and resistor 19 a common potential point at one terminal of the plate load of tube 2 consisting of resistor 15' and inductance element 16'. In this manner, any tendency of the amplifier system to oscillate at a low frequency is eliminated. In order not to degenerate the useful signal applied to the tube 3, the frequency selective network comprising condenser 14'', resistor 19 and condenser 18' is so designed as to pass the low frequencies only at which the amplifier system tends to oscillate.

While the same novel feature could be inserted in other stages of the amplifier system, that is, the connection of the screen grid of the following tubes by way of selective network to the output circuit of the preceding tube, this was not found necessary since the greatest danger of oscillation generation exists in the last stage of an amplifier system, since the signal level there is the highest. If found necessary, however, similar connections could be made between other stages of the amplifier system.

The particular embodiment of the invention is a television picture signal amplifier system, in which the following tubes and circuit constants were found to operate effectively.

Tube 2	6AC7
Tube 3	6AG7
Resistor 15'	ohms 1650
Inductance element 16'	microhenrys 25
Resistor 17'	ohms 6000
Resistor 19	do 4000
Condenser 18'	microfarads 10
Condenser 14'	do 10

the condensers and resistors used all have relatively small values.

While there has been described what is at present considered the preferred embodiment of the invention, it will be obvious to those skilled in the art that various changes and modifications may be made therein without departing from the invention, and it is, therefore, aimed in the appended claims to cover all such changes and modifications as fall within the true spirit and scope of the invention.

What is claimed is:

1. An amplifier system comprising a plurality of amplifier tubes connected in cascade relation, each having an anode, a common source of operating voltage for said anodes, a load impedance connected to the anode of one of said tubes, means including an impedance element for connecting said anode through said load impedance to said voltage source, an electrode in a second of said tubes immediately following said first-named tube in said amplifier, said electrode being adapted to collect a portion of the electron stream in said second tube and also adapted to be maintained at a substantially steady potential, and means including a selective network connected between said load impedance and said impedance element for connecting said electrode to said voltage source.
- 15 2. An amplifier system comprising a plurality of amplifier tubes connected in cascade relation, each having an anode, a common source of operating voltage for said anodes, a load impedance connected to the anode of one of said tubes, means including an impedance element for connecting said anode through said load impedance to said voltage source, a screen grid electrode in a second of said tubes immediately following said first-named tube in said amplifier, and means including said impedance element for connecting said electrode to said voltage source and said load impedance and developing a pulse to counteract a pulse of the opposite polarity in said load impedance.
- 25 3. An amplifier system comprising a plurality of amplifier tubes connected in cascade relation, each having an anode, a common source of operating voltage for said anodes, a load impedance connected to the anode of one of said tubes, an electrode in a second of said tubes immediately following said first-named tube in said amplifier, said electrode being adapted to collect a portion of the electron stream in said second tube and also adapted to be maintained at a substantially steady potential, and means including an impedance element for connecting said electrode and said load impedance to said voltage source to develop a feed-back voltage in said load impedance.
- 40 4. An amplifier system, comprising a plurality of amplifier tubes connected in cascade relation, each having an anode, a common source of operating voltage for said anodes, a load impedance connected to the anode of one of said tubes, an electrode in a second of said tubes immediately following said first-named tube in said amplifier, said electrode being adapted to collect a portion of the electron stream in said second tube and also adapted to be maintained at a substantially steady potential, and means including a low pass filter and an impedance element for connecting said electrode and said load impedance to said voltage source.
